United States Patent Office.

WILLIAM M. SMITH, OF AUGUSTA, GEORGIA.

Letters Patent No. 97,977, dated December 14, 1869.

IMPROVEMENT IN COTTON-BALE TIES.

The Schedule referred to in these Letters Patent and making part of the same.

To all whom it may concern:

Be it known that I, WILLIAM M. SMITH, of the city of Augusta, in the county of Richmond, and State of Georgia, have invented a new and improved Cotton-Bale Tie; and that the following is a full, clear, and exact description of the same, reference being had to the accompanying drawings, making part of this specification, in which—

Figure 1 represents in perspective the tie uniting the two ends of an iron band, as when applied in binding cotton-bales.

Figure 2 represents the tie as it should be adjusted to the band, preparatory to uniting the two ends of the same together.

Figure 3 represents the tie uniting the two ends of the iron band, but not entirely adjusted.

Similar letters of reference, where they occur in the separate figures, denote like parts in all the drawings.

My invention relates to an improvement in cotton or other bale-ties; and consists of a flat rectangular piece of iron, having a square opening through the centre, slightly larger than the width of the iron band, and a Y-shaped slot through one of its sides, for the better adjustment of said band.

To enable others skilled in the art to make and use my invention, I will proceed to describe the construction of the same, with reference to the drawings.

A' A" A''' A'''' represent the four corners of a flat piece of iron, A, of an even surface, and about two inches square by an eighth of an inch thick.

B' B" B''' B'''' represent the four corners of a square hole, B, cut in the middle of said piece. The sides of the said hole should always be made to exceed in length, very slightly, the width of the iron or other metallic band designed to be used in combination with said piece.

C represents a Y-shaped aperture, cut in one side of piece A.

One side of said aperture, marked x, is made blunt at the end, as seen at a.

The opposite side, x', is pointed, as seen at a', to prevent the band slipping out of the tie during the final adjustment of the same around the bale.

When the piece A is made of flat iron, the aperture should always be made as represented in figs. 1, 2, and 3, in order to facilitate the passage of the looped ends of the iron band D D into the hole B, and the proper adjustment of the tie, as seen in fig. 1.

To unite, properly, the two ends of the iron band D D, around a cotton or other bale, with the piece A' A" A''' A'''' bend and interlock one end of said band with said piece, as represented in fig. 2, pass the other end around the bale, and ascertain, by measurement with the band, its excess in length over the circumference of the bale to which it is being applied; bend inwardly the end of the band in excess, bring the two ends together, and unite the last end bent, by passing the loop thus made horizontally, either to the right or to the left, as may be necessary, through aperture C

into the square hole B; retract and interlock the two ends of said band with said piece, as represented in fig. 3. After thus uniting the two ends of the band with the piece A, take hold, with the left hand, of the upper left-hand corner of the same, as indicated by the arrow in fig. 3, holding at the same time, with the right hand, the other end of the band, below the tie. Then bring the two ends together, and turn the tie in the direction indicated by the pointing arrow, until the aperture C passes under the looped end of band D D, as fully represented in fig. 1, which completes the proper adjustment of the tie when uniting the ends of the band D D, as applied in binding cotton-bales.

The aperture C should be cut of sufficient width only, to admit freely into the hole B, the looped ends of the band D D. When the looped ends of band D have been united, as represented in fig. 3, by means of the tie under consideration, and the attempt is made to adjust the same, as heretofore directed, the edge of the looped end of said band will pass as freely over the slot C as if it were not in the piece A. This result is attained by the peculiar construction of the slot C.

It may be observed, that the interior corner a, of the slot C, is cut off, and the opposite corner, a', presents an acute angle.

In turning the piece A, as directed, of fig. 3, until adjusted as represented in fig. 1, the edge of the looped end of band D will drop from the acute corner a', upon the incline made by cutting off the corner a, and pass the slot C without the least interruption. Any other construction of said slot would certainly result in perplexing delay.

It was purposely conceived and executed in the construction of the piece A, that the dimensions of the square hole B should be made to exceed, very slightly indeed, the width of the band D, to the end that more of the slack of said band might be taken up when being applied to cotton-bales, than could possibly be done if said piece had an oblong hole instead of the one herein represented.

Thus, it will be perceived, that the square hole B and the peculiar construction of the slot C, possess valuable characteristics, not believed to be shown in any other bale-tie now in use.

I do not claim a rectangular cotton-bale tie, provided with a V or X-shaped slot, for these I know to be old; but

What I do claim, and desire to secure by Letters Patent, is—

An improvement upon rectangular cotton-bale ties, with V or X-shaped slots, said improvement consisting in striking off the interior point or angle a, while the point or angle a' is left entire, for the ready and secure adjustment of the loop-band D, as herein shown and described.

Witnesses: WILLIAM M. SMITH.

EDMUND MASSON,
D. BALLAUF.
